TRACTION CHAIN SHOE

Arne Lars Mathisen, Sandvika, Norway

Application August 25, 1952, Serial No. 306,170

Claims priority, application Norway
August 27, 1951

7 Claims. (Cl. 305—10)

1

The present invention relates to shoes of the type adapted to be used in connection with chains for the moving of vehicles, for the transport of goods and for other purposes wherein it is desirable to provide each or some chain links with an increased traction promoting surface, i. e. an increased ground engaging surface in the case of a vehicle and an increased goods supporting surface in the case of a transport chain. For the purpose of increasing the frictional effect of such shoes it is previously commonly used to provide the same with freely projecting pikes or prods or with flanges or ribs extending perpendicularly to the direction of movement of the shoe. Such engaging devices usually are made of a hard material of great wearing strength, such as steel, with the consequence that when the same knock against fragile objects or when running on made roads or streets they are apt to provoke damages, both to the objects encountered, the road or street surface and to the driving means of the vehicle or to give rise to skidding when encountering hard objects, such as stones or when running on stone or stone pavement.

The object of the present invention is a shoe adapted for cooperation with objects or surfaces of any kind, without endangering the shoe itself or the driving means of the same and at the same time presenting such a frictional effect that skidding in any direction is prevented.

For this purpose a shoe according to the present invention comprises a base structure carrying a number of substantially U-shaped elements made of a yielding, resilient material arranged with the two legs of each U-shaped element following one after the other in the direction of movement of the shoe and means interconnecting the said base structure and the free ends of the said U-shaped members. When such a shoe is loaded, the U-shaped elements will carry the load while tilting over on one of the legs, thereby presenting not only a soft engagement but also a resilient friction against the surface contacting the shoe.

The base structure carrying the U-shaped elements suitably comprises a number of batten or bar formed members extending parallelly transversely to the direction of movement of the shoe and being adapted to be connected in common to a chain link, thereby providing a very simple manner of mounting. Simultaneously the arrangement of the individual U-shaped elements relatively to each other, the number of the same and the width of the shoe are all easily adaptable to the conditions under which the chain is to operate. Thus, the U-shaped elements may

2

be held between adjacent battens with the two legs contacting each other, or the elements may be so arranged that they are covering one or more battens and, if desired, even other U-shaped elements, to the effect that it is possible to adjust the softness of the engagement between the shoe and the surface contacted, and the friction presented against the same. The battens between which the U-shaped elements are clamped 10 may be made of any suitable material, but are preferably made with surfaces or provided with surface portions of increased friction on the faces contacting the elements to be held, to the effect that the elements are not only kept in position by means of special connecting devices such as screws or bolts, but are also held by friction against the battens.

The U-shaped elements may be made of any suitable material, according to the use of the 20 chain, but for particularly heavy vehicles such as tractors, bulldozers or military vehicles it is found suitable to use sheets of vulcanized rubber, preferably of such composite construction as that used in the tread of a tire.

The accompanying drawing illustrates some 25 embodiments of a shoe according to the invention.

Figure 1 is a perspective view partly in section of a shoe according to the invention as mounted 30 on an associated chain link, while the Figures 2 to 5 are fractional sectional views of various forms of U-shaped elements and their base structure, and the Figures 6 to 8 are fractional plan views illustrating various distributions of the U-shaped elements relatively to a base structure.

In the drawing, 1 is the U-shaped elements and 2 the battens constituting the base structure and between which the elements 1 are held, the battens 2 being clamped together and the elements held between them by means of bolts 3, so 40 as to make a solid assembly which may be connected to a link of the chain. In the embodiment shown in Fig. 1, the chain is composed of links comprising at least two mutually parallel members 4, the interconnecting pivot pins of the same being omitted for the sake of clarity, and the shoe assembly is connected to the link members 4 by means of bolts passing through holes 5 in the battens 2. As illustrated, the width of the shoe may be greater than the width of the 50 link combination, whereby an increased shoe surface is obtained. As indicated, the exterior front and rear battens 2' of a shoe may be made of a reduced cross sectional area as compared with that of the intermediate battens 2. The battens 55 may be made solid, for instance of hard wood or

iron and provided with a friction increasing coating 6 (Figs. 2 to 5) which may be arranged around the total circumference of the batten as shown, or on such surfaces only between which the elements 1 are to be clamped, or the battens may be made tubular with a corresponding friction coating or they may be made solid of a material which in itself presents the desired friction, such as hard rubber.

As shown in the Figures 2 to 5, the U-shaped elements 1 may be arranged in various manners relatively to the battens 2 clamping the same and in the Figures 6 to 8 some examples are shown of possible distributions of the elements 1 relatively to each other and to the length of the battens.

I claim:

1. A traction chain shoe comprising a base structure and a plurality of substantially U-shaped elements made of a yielding, resilient material arranged with the legs of each individual U-shaped element in parallel relation substantially transversely to the principal direction of movement of the shoe, and means interconnecting the said base structure and the free ends of the legs of each of the said U-shaped elements.

2. A shoe as claimed in claim 1, wherein the shoe base structure comprises a plurality of mutually parallelly disposed members extending transversely to the principal direction of movement of the shoe, the free end of each leg of each of the U-shaped members being clamped between adjacent base structure members.

3. A shoe as claimed in claim 1, wherein the shoe base structure comprises a plurality of mutually parallelly disposed members extending transversely to the principal direction of move-

ment of the shoe, the free ends of both legs of a U-shaped member being clamped between adjacent base structure members.

4. A shoe as claimed in claim 1, wherein the shoe base structure comprises a plurality of mutually parallelly disposed members extending transversely to the principal direction of movement of the shoe, the free ends of the legs of a U-shaped member being clamped between spaced sets of adjacent base structure members.

5. A shoe as claimed in claim 1 comprising a plurality of mutually parallelly disposed members extending transversely to the principal direction of movement of the shoe and a number of substantially U-shaped members arranged with the free end of each of the legs of the same in clamped relation between adjacent members of the said transversely disposed members, the said members being provided with friction promoting surface portions.

6. A shoe as claimed in claim 1 comprising a plurality of mutually parallelly disposed members extending transversely to the principal direction of movement of the shoe and a number of substantially U-shaped members arranged with the free end of each of the legs of the same in clamped relation between adjacent members of the said transversely disposed members, the said members being made of a material of substantial surface friction effect.

7. A shoe as claimed in claim 1, wherein the various U-shaped members are arranged in interspaced relation.
